Primary Examiner — Mitchell I. Siegel*(74) Attorney, Agent, or Firm* — Michael E. Tschupp(57) **CLAIM**

The ornamental design for a built-in home appliance, as shown and described.

DESCRIPTION

FIG. 1 is a front perspective view of a built-in home appliance showing a first embodiment of our new design;

FIG. 2 is a front view thereof;

FIG. 3 is a rear view thereof;

FIG. 4 is a top view thereof;

FIG. 5 is a bottom view thereof;

FIG. 6 is a right side view thereof;

FIG. 7 is a left side view thereof;

FIG. 8 is a front perspective view of a built-in home appliance showing a second embodiment of our new design;

FIG. 9 is a front view thereof;

FIG. 10 is a rear view thereof;

FIG. 11 is a top view thereof;

FIG. 12 is a bottom view thereof;

FIG. 13 is a right side view thereof; and,

FIG. 14 is a left side view thereof.

The broken line showing is included for the purpose of illustrating unclaimed subject matter and forms no part of the claimed design.

1 Claim, 14 Drawing Sheets(56)
